ATTORNEY

UNITED STATES PATENT OFFICE.

PATRICK D. SKAHEN, OF SYRACUSE, NEW YORK.

BURIAL CASKET.

Application filed December 15, 1928. Serial No. 326,183.

This invention has for its object a particularly simple and economical construction of a sheet metal burial case which can be readily and permanently sealed after the 5 casket has been placed therein.

The invention consists in the novel features and in the combinations and constructions hereinafter set forth and claimed.

In describing this invention reference is 10 had to the accompanying drawing in which like characters designate corresponding parts in all the views.

Figure 1 is a plan view of this burial case.

Figure 2 is a fragmentary sectional view 15 on line 2—2, Fig. 1.

Figure 3 is a detail view of the lock or latch for securing the housing on the base.

This burial case comprises generally a sheet metal base having an upturned marginal flange around the same, a box like housing open at its lower side mounted on the base and spaced apart from said flange forming a channel for receiving a sealing medium as cement, the housing preferably 25 having an outwardly extending base flange which spaces it from the former flanges and which forms the bottom of the channel.

The invention also preferably includes 30 latching means for securing the housing to the base, said latching means being located in the channel in position to be embedded in the cement or other sealing medium.

1 designates the base which is formed of 35 sheet metal with an upwardly extending marginal flange 2 preferably extending entirely around the base 1 so that the base is in the form of a shallow pan.

3 designates the box like housing mounted 40 on the base, the housing being open at its lower side and formed with an outwardly extending marginal flange 4 at its lower edge, the housing being arranged with its lower margin spaced apart from the flange 2 and thereby forming a channel 5. 45 The flanges 4 are arranged to form the bottom of the channel.

When a sealing medium is filled into the channel the housing and the base are securely and hermetically sealed. The housing 50 55 3 is formed of sheet metal and comprises, top, side and end walls, each side wall and one portion or the corresponding half of the top are preferably formed as a unit of metal and the top sections or halves have upwardly extending abutting flanges

6 which are secured together as by spot welding.

The end walls 7 are inset and formed with outwardly extending marginal flanges 8 forming channels 9 along the ends of the case corresponding to the channels 5. The flanges of the end walls 7 along the lower edges thereof correspond to the flanges 4 of the side walls of the housing 3. The flanges 8 of the end walls are secured to the 60 margins of the side walls and tops in any suitable manner as spot welding.

Means is provided for securing the housing to the base so that the case can be transported before being sealed to the place of 65 burial.

This latching means is preferably located in the channel 5. As here shown, it includes a plurality of latches, each of which includes a flange or shelf 10 extending 70 laterally from the side walls of the housing; a keeper 11 overhanging one end of the flange or shelf 10, a latch member 12 pivoted on a vertical axis at 13 near the other end of the shelf and being arranged to 75 swing under the keeper 11 and a movable lug 14 secured to the base 1 or the flange 2 thereof and movable onto the shelf 10 into a position to be under the latch 12 when it is swung into engagement with the keeper 80 plate 11. The flange or shelf 10 is one side of an angle iron which is secured to the lower margin of the side walls of the housing as by rivets 15. The keeper 11 has a base flange 16 between the angle iron and 85 the side walls of the housings, suitable handles 17 are provided on the housing.

In operation, the housing and the base can be temporarily secured together for the purpose of transporting it and the housing 90 removed for the purpose of replacing the casket on the base 1. After the casket has been placed on the base 1, the housing is placed on the base and the parts permanently secured and sealed together. The subject 95 matter of this invention is substantially the same as that of applicant's prior application Sr. No. 43,724 filed July 15, 1925, allowed October 31, 1927 and forfeited and not renewed.

What I claim is:

1. A burial casket comprising a base plate having an upturned marginal flange and a box like top portion open at its lower side for resting on the base within said 100 105 110

flange, upright walls of the housing having outwardly extending spacing flanges at their lower edges, the first mentioned flanges with the lower margins of the upright walls of the housing forming a channel for receiving a sealing medium and latching means associated with the base and the housing and located within the channel, said latching means comprising a horizontal shelf fixed to the housing and extending laterally therefrom, a keeper overhanging one end of the shelf, a latch pivoted to the plate near its other end on an upright axis and movable under the keeper, and a movable lug secured to the base and movable over the plate in position to be between the plate and the latch when the latch is engaged with the keeper.

2. A burial casket comprising a base plate and a box like housing on the base plate, the housing being open at its lower side and comprising side, top and end walls, the top being formed in sections and each section

being a unit with one of the side walls and the top sections having abutting flanges secured together, the end wall being formed with an angular marginal flange and being inset with said flanges confronting the margins of the side walls and the margins of the top walls and secured thereto.

3. The casket of claim 2 in which the base is formed with an upturned marginal flange around the same forming a channel with the lower margin of the housing for receiving a sealing medium, the side walls having outwardly extending base flanges forming the bottom of the channel and the end walls having outwardly extending flanges forming the bottom of the channels at the ends of the burial case.

In testimony whereof, I have hereunto signed my name, at Syracuse, in the county of Onondaga, and in the State of New York, this 13th day of December, 1928.

PATRICK D. SKAHEN.
